CLOSURE AND CONTACT FOR MERCURY SWITCHES

Ernst Walter Rickmeyer, Berkeley, Ill., assignor to Jefferson Electric Company, Bellwood, Ill., a corporation of Illinois

Application December 13, 1945, Serial No. 634,777

2 Claims. (Cl. 200—152)

1

The present invention relates to mercury switches, and particularly to an electrode or contact assembly for hermetically sealing the switch envelope or shell.

A mercury switch of the type that would employ the present invention may include a shell, open at one end, that has a partition spaced intermediate the ends of the shell. This partition divides the shell into two chambers, and is provided with restricted openings therein through which a conducting fluid (mercury) may pass.

A quantity of mercury is contained in one of the chambers and under certain conditions is adapted to flow into the second chamber through the restricted passages in the partition. An electrical contact member projects into the shell through the open end thereof, and means are provided for hermetically sealing this open end of the shell. The mercury bridges a gap between this first contact member and a second contact so as to close an electrical circuit through the switch.

The invention is concerned with the first contact member and the means for hermetically sealing the end of the switch shell through which this contact projects.

It is an object of the invention to provide an effective arrangement for sealing the end of a mercury switch shell of this type while at the same time providing a terminal connection to the contact member with a very low electrical resistance. In other words, the invention has the dual purpose of effectively sealing the open end of the switch shell while at the same time providing a low resistance path to the mercury through this end of the shell. This is accomplished very effectively in a simple and inexpensive manner, and by means that are readily adaptable to mass production methods.

The foregoing constitute some of the principal objects of the present invention, and others will become apparent from a reading of the following description and from the drawings, in which:

Fig. 1 is a vertical sectional view taken through a completely assembled mercury switch that embodies one form of the present invention;

Fig. 2 is a top plan view of the switch shown in Fig. 1;

Fig. 3 is a fragmentary vertical sectional view corresponding to Fig. 1, but showing a different embodiment of the invention;

Fig. 4 is a side elevational view of the electrical contact element shown in Fig. 3;

Fig. 5 is a top plan view of the element shown in Fig. 4;

2

Fig. 6 is a vertical sectional view taken through a contact member illustrating a slightly different form of contact element;

Fig. 7 is a bottom plan view of the device shown in Fig. 6;

Fig. 8 is a fragmentary vertical sectional view corresponding to Fig. 3, but showing still another embodiment of the invention; and

Fig. 9 is a view corresponding to Fig. 8, but showing a different embodiment of the invention.

For purposes of illustration, specific embodiments of the invention have been selected, it being recognized that many different modifications will occur to the man skilled in the art. It is intended that many of these modifications may be made without departing from the scope of the invention.

Referring to the drawings, and particularly to Fig. 1, the invention is shown as applied to a mercury switch, generally indicated at 15, and comprising a switch shell 16 that is open at one end and is provided with an annular shoulder 17 intermediate the ends of the shell for supporting a cup-like time delay element 18. As shown, this cup 18 comprises sintered metal particles between which are a plurality of voids forming restricted passages. This cup 18 divides the shell 16 into chambers 19 and 20.

A contact member 21 is adapted to pass through the open end of the shell 16 and to project as at 22 into the chamber 19. This contact member 21 has an annular flange or shoulder 23 adjacent to the upper end thereof that is supported on the top edge of the cup 18. A copper ring 24, provided with a flange 25, is adapted to pass through the open side of the cup 18 with the flange 25 resting on the top edge of the cup. A fiber washer 26 is disposed on the flange 25, and the shoulder 23 of contact member 21 rests on this fiber washer 26. A second fiber washer 27 surrounds the upper end of the contact member 21 and rests on top of the shoulder 23. The shell 16 is crimped over at 28 onto the last mentioned fiber washer 27, and is pressed firmly against this washer so as to effectively seal the contact member 21 into the open end of the shell 16.

This contact member 21 is made of a material that has the property of readily conducting electrical current. A boss-like portion 29, indicated in broken lines, is initially provided at the upper end of the contact member 21, and a copper ring 30 is adapted to fit circumferentially and snugly about this boss-like projection 29. This boss-like projection 29 is then riveted over as shown at 31 to form an attacking means to firmly secure the

copper ring 30 to the contact member 21, and to insure good electrical conductivity between this copper ring 30 and the contact member. The copper ring 30 is provided with a terminal extension portion 32 to which a lead wire may be attached. A second copper ring 33 may be mounted concentrically about the lower portion of the switch shell 16, as shown, and a second lead wire may be secured to this latter ring.

A body of mercury 34 is shown disposed in chamber 19 so that an electrical circuit from the electrical conductor 32 to the copper ring 33 is completed through the conducting member 21, mercury 19, time delay cup 18, and finally through the wall of the shell 16.

If the switch shell is spun about an axis that is disposed above the shell 16 so that under the influence of centrifugal force the mercury 34 is forced against the bottom wall of the cup 18, the mercury will pass through the restricted openings between the sintered metal particles and flow into the lower chamber 20. A certain time delay is required to pass this mercury through the bottom wall of the cup into the lower chamber 20 due to the fact that air in the chamber 20 must be displaced, and this air must necessarily pass in a reverse direction through the restricted interstices between the metal particles into chamber 19. As soon as the mercury has passed into chamber 20 in a sufficient amount to lower the mercury level in chamber 19 to a position below the lowermost contact portion 22 of contact member 21, the electrical circuit through the switch has been broken.

The arrangement shown in Fig. 1 insures an effective seal of the open end of the switch shell 16. It is important that air be initially evacuated from the shell 16 and at all times be prevented from leaking into chamber 19 in order to prevent the occurrence of oxidation to thereby insure at all times good electrical contact between the mercury and the contact member 21.

Since the entire contact member 21, as shown in Fig. 1, is made of metal, it is essential that all parts of this contact member be electrically insulated from the shell 16 and the time delay cup 18. As shown, the fiber washers 26 and 27 serve to insulate the contact member and to space the shoulder 23 thereof from the walls of the shell 16.

It may be desirable to provide a contact member that is mostly non-metallic and that in itself is non-conductive. In Fig. 3, such an arrangement is shown, where a contact member, generally shown at 35, comprises a plug or end closure portion 36 of Bakelite, or like non-conducting material, that is molded about a cup-like or cup-shaped electrical conducting element 37. This plug 36 is provided with an annular shoulder 38 that corresponds with the shoulder 23, previously described. The manner of sealing this plug 36 in the open end of the cup shell is in accordance with that previously described in connection with the contact member 21 of the first embodiment of the invention. The cup-like or cup-shaped contact element 37 per se is shown in Figs. 4 and 5, and comprises an upwardly opening cup-like or cup-shaped portion 39 having an upstanding lead or electrical conducting member 40 for securing thereto an electrical conductor. The entire contact element 37 may be made of copper or some other such material having high electrical conductivity.

As shown in Fig. 6, a similar arrangement to that shown in Fig. 3 may be utilized, but in this instance a conducting element 41 may be em-

ployed where the lower portion, indicated at 42, constitutes a ring rather than a cup-like portion 39, as shown in Fig. 4.

In Fig. 8, a somewhat different form of the invention is shown. In this instance, a plug 43 is employed together with a cup-like element 44 that completely encloses a downwardly projecting boss 45 forming part of the plug 43. In this instance, the lower portion of the conducting element 44 is in the form of a cup 46 that is relatively deep and is flared as at 47. This flared portion 47 is contained within the body of the plug 43, as was the case with the plug 35 shown in Fig. 3. This plug 43, together with its downwardly extending boss portion 45, may be made of Bakelite, and, again, is provided with an outwardly extending annular flange or shoulder portion 48. This shoulder portion 48 is adapted to be supported on the time delay cup 18 in the mercury switch shell 16. In this case, however, a seal is effected by an irregularly shaped copper ring element 49 that passes between the wall of the shell 16 and the side and lower faces of the annular shoulder 48. This sealing ring 49 has a downwardly extending flange 50 that projects into the time delay cup 18, and also is provided with an upwardly extending flange portion 51 that is crimped inwardly upon the top surface of the shoulder 48. The upper edge 28 of the shell 16, in this instance, is crimped over onto the ring flange 51, and then this last named flange is curved backwardly against the crimped over portion 28 of the shell. In this manner, the open end of the shell 16 is effectively sealed. In this embodiment of the invention, the walls of the cup 46 are exposed to the interior of chamber 19, and are subject to be contacted by the mercury in this chamber throughout substantially the entire depth of this cup portion 46. Thus, in this form of the invention, a longer contact between the mercury and the contact element 44 can be effected than in the case of the embodiment shown, for example, in Fig. 3.

Fig. 9 illustrates still another embodiment of the invention. In this instance, the contact member, generally shown at 55, comprises a metallic contact element, generally indicated at 56, that is supported by an insulating portion 57 of Bakelite or like material. This contact portion 56 is provided with a lower end portion 58 having an upwardly extending portion 59 of less diameter. The insulating portion may be molded circumferentially by the upstanding portion 59 of the contact member, and is provided with an annular shoulder 60 that serves in the same manner as the previously disclosed shoulders 23, 38, and 48, for example. In this embodiment of the invention, the central portion 59 of the contact member 56 initially projects above the insulating portion 57, as indicated in broken lines at 61, and a copper ring 62 is mounted over this projecting portion. This ring 62 is firmly held against the top of the insulating portion 57 by riveting over the upstanding portion 61, as shown at 63. Good electrical conductivity again is provided between the ring 62 and the contact portion 56.

As in the case of the embodiment shown in Fig. 1, the copper ring 24 with its outwardly extending flange 25 is provided at the open end 70 of the time delay cup 18, the flange 25 resting on the top edge of the cup 18. A gasket 64 is inserted between the shoulder 60 and the shell 16 and flange 25 of ring 24. This gasket 64 is provided with an upper portion 65 that is bent 75 over onto the top surface of the shoulder 60,

and then the open edge 28 of the shell 16 is crimped over against this portion 65 of the gasket with sufficient pressure to effectively seal the open end of the shell.

The ring 62 corresponds with ring 30 in the embodiment shown in Fig. 1 and serves as one terminal connection to the mercury switch. A second ring 33 is provided, as before, to serve as the second terminal connection to the switch.

In this form of the invention, an electrical circuit through the switch is completed so long as the mercury is in engagement with the exposed surfaces of the lower portion 58 of contact element 56.

I claim:

1. A contact member for use in an open shell of the type described comprising an open cup-shaped contact portion, an upstanding elongated conductor attached to the side wall of the cup, a closure portion in said cup-shaped portion and projecting thereabove, said closure portion including an annular shoulder projecting laterally beyond the outer limits of the cup-shaped portion, the conductor passing through the closure portion and connecting the cup-shaped portion with means adjacent to the top of the closure

portion for attaching thereto an electrical conductor.

2. In a mercury switch, a shell having an open end, an annular shoulder in the shell adjacent to the open end thereof, a contact member including an end closure portion for the shell, and electrical conducting means projecting through the contact member into the shell interior, said contact member including an upwardly opening cup-shaped member of electrical conducting material having outside surfaces exposed to the interior of the shell, and mercury in the shell for conducting an electrical current from outside the shell to the cup-shaped portion.
